(57) **CLAIM**

The ornamental design for a latch arrangement for a battery pack, as shown and described.

DESCRIPTION

FIG. 1 is a front perspective view of a latch arrangement for a battery pack showing our new design;

FIG. 2 is a bottom plan view of the latch arrangement;

FIG. 3 is a left side elevational view of the latch arrangement; and,

FIG. 4 is a right side elevational view of the latch arrangement.

In the above drawings, any broken line illustration is not part of the design sought to be patented. In addition, any views not shown thereof do not form a part of the invention.
